UNITED STATES PATENT OFFICE

DAVID LARKIN, OF WEBSTER GROVES, MISSOURI

FURNACE

Application filed May 27, 1929. Serial No. 366,430.

This invention relates broadly to furnaces and the like, and has more particular reference to a furnace used for heating kettles and the like containing oil or other substances that are being boiled or otherwise heat-treated therein and which may be easily ignited accidentally if placed over an open flame in the ordinary manner.

The principal purpose of the invention is to provide a furnace having an opening over which to place kettles and other external objects to be heated, and in which the flame is projected from the combustion chamber squarely against the kettle and doubled back upon itself and withdrawn into a flue instead of being forced out of the opening and over the sides of the kettle.

Other objects and advantages, some of which are more or less ancillary to the main purpose of the invention, will appear in the course of the following description of a preferred embodiment of this invention.

In the accompanying drawings forming part of this specification, in which like numbers of reference denote like parts wherever they occur,

Figure 1 is a plan view of a furnace constructed in accordance with this invention;

Figure 2 is a vertical sectional view taken on the line 2—2 in Figure 1;

Figure 3 is a front elevation taken on the line 3—3 in Figure 2;

Figure 4 is a transverse vertical sectional view taken on the line 4—4 in Figure 2;

Figure 5 is a plan view of a battery of furnaces, showing the manner of connecting them to the breeching; and

Figure 6 is a transverse vertical sectional view taken on the line 6—6 in Figure 2.

The furnace is preferably installed in the basement 1 of a suitable building 2 immediately under the ceiling 3, a hole 4 being made in the concrete floor slab 5 which separates the basement from the floor above. The hole 4 is preferably cylindrical, and is lined with

a ring 6 of refractory material, which projects below the bottom of the slab 5. The furnace comprises side walls 7, disposed on opposite sides of the duct or opening 4, front wall 8, rear wall 9, bottom wall 10, and arched top walls 11 and 12. Arch 11 covers the spraying chamber 13 at the front portion of the furnace, and the spraying chamber 13 enlarges upwardly at its rear end into a combustion chamber 14, the arch 12 of the combustion chamber being connected to the arch 11 by a vertical offset wall 15. Rear wall 9 has a forwardly and downwardly stepped lower portion 16, and the upper portion of the wall extends vertically upward through the duct 4 nearly to the level of the top of the slab 5, dividing the duct into a passage 17 of substantially semi-circular cross-section and into a passage 18 on the other side of the wall 9. The wall 9 and steps 16 are arcuate in horizontal cross-section, presenting their convex side 19 to the combustion chamber 14 and passageway 17. The concave side 20 of the passageway 17 is corbeled at its lower end or juncture 21 with the vaulted ceiling 3 and side walls 4. The bottom of the furnace rests on channel beams 22, the ends of which are supported on walls 23, forming downward continuations of the walls 7 to the basement floor 24. The front and side walls 8 and 7 are reinforced and braced by an angle-iron framework 25, secured at the bottom to the beams 22 and at the top cemented in recesses or pockets 26 formed in the underside of the slab 5. Suitable brick 27 may be interposed between the floor beam 28 and the wall 15.

A transverse wall 29 behind the wall 9 extends from basement floor 24 to a height approximately midway between the bottom of the furnace and the floor slab 5. A pair of spaced apart channel beams 30 bridge the space intervening between the wall 29 and the outer wall 31 of the building, one end of each channel resting on the wall 29, and the other end being cemented in a recess 32 in the

wall 31. Walls 33 are built on the channels 30 from a breeching 34 to the wall 9. A horizontal block of tile 35, supported at opposite sides in recesses 36 in the lower portion 5 of the walls 33, and a horizontal block of tile 37, supported at opposite sides in recesses 38 in the upper portion of the walls 33, in conjunction with the walls 33, form a flue 39 conveying the products or gases of combustion from the passageway 18 to the breeching 34.

An angle iron 40 is secured to the top side of the slab 5 at the rear of the opening 4 and transversely to the furnace by any suitable fastening means, such as expansion bolts (not shown), the floor slab 5 preferably being recessed to receive the horizontal flange 41 of the angle iron 40 so that the upper surface of the flange 41 is on a level with the top 20 of the floor. Channel beams 42 are arranged transversely to the iron 40 on either side of the opening 4, and have one of their ends superimposed on the angle iron 40 and secured thereto by a clamping plate 43 and bolt 44. 25 The beams are arranged with their flanges 45 projecting upwardly and serve as guides for the wheels of a portable kettle, not shown, that is to be placed over the opening 4.

The fuel used in the furnace is preferably 30 oil, and a combustion block 46, having a central opening 47 therein for the introduction of air and oil to the furnace, fits in an opening 48 therefor in the front wall 8 of the furnace so as to be easily removable. Other openings 35 49 in the wall 8 on either side of the opening 48 are closed with loosely fitting blocks or bricks 50, which may be easily removed to permit inspection of the interior of the furnace and to admit more or less additional air to the chamber 13.

Fuel oil passes from the pipe 51, and compressed air from the pipe 52, to the injector 53, which projects an atomized mixture of air and oil through the opening 47 into the 45 spraying chamber 13 and also against the stepped splash wall portion 16. The fuel burns in the chamber 14, the ignited gases and products of combustion rushing upwardly through the passage 17 against the bottom 50 of the kettle and then being deflected laterally through the shallow space over the top of the wall 9 and down into the passageway 18 and from thence through the flue 39 into the breeching 34. The shallow space above 55 the wall 9 insures that the flame will touch the bottom of the kettle, and the arcuate shape of the wall 9 insures that a flame of maximum horizontal dimension will pass across the opening 4. A plurality of furnaces 60 may be placed in a row and connected in parallel to the breeching 34 and to the oil and air piping 51 and 52. The breeching 34 may lead to a chimney 54, and the draft in the flue may be increased, if necessary, by suitable means not shown, such as a blower or in-

jector, or by connecting a boiler to the breeching. The walls 9 and 33 forming sides of the passageway 18 are preferably beveled at their upper ends as at 55 to assist the flow of heated gases into the passageway 18.

70

Having thus fully described this invention, I hereby reserve the benefit of all changes in form, arrangement, order, or use of parts, as it is evident that many minor changes may be made therein without departing from the spirit of this invention or the scope of the following claims.

75

I claim:

1. A furnace having an upright duct open at the top, a transverse vertical wall in the duct extending nearly to the top and dividing the duct into separate passageways for ascending and for descending gases and presenting a horizontally convex-arcuate side to the passageway for the ascending gases thereby by increasing the cross-sectional area thereof, a combustion chamber communicating with the lower portion of the last-mentioned passageway, and a flue communicating with the lower portion of the other passageway.

80

2. A furnace having a vertical duct open at the top, a transverse vertical wall in the duct extending nearly to the top and dividing the duct into separate passageways for ascending and for descending gases, the side of the wall presented to the passageway for the descending gases being beveled at its upper edge to increase the cross-sectional area of the entrance of the passageway for descending gases, a combustion chamber communicating with the lower portion of the passageway for the ascending gases, and a flue communicating with the lower portion of the other passageway.

85

3. A furnace having a vertical duct open at the top, a combustion chamber having a transverse rear wall extending upwardly through the duct nearly to the top thereof and dividing the duct into separate vertical passageways both passageways being within the confines of the opening in the top, one of which has its lower end opening into the top of the combustion chamber, and a flue opening into a side of the other passageway.

90

4. A furnace for atomized fuel having a spraying chamber communicating with an opening for the introduction of fuel thereto, and presenting a combustion chamber disposed rearwardly and upwardly of said spraying chamber, said furnace being further provided with an open duct extending upwardly from said combustion chamber and a transverse wall forming the rear of said last-named chamber and adapted to divide said duct into passageways of unequal cross-sectional area, said wall terminating below the top of said duct to define a horizontal passageway communicating with the passageways formed by said wall.

95

5. A furnace presenting a combustion

chamber and an opening positioned there-
above, and a wall extending nearly to the top
of said opening to define a passageway for
ascending gases and a passageway for de-
5 scending gases, said last-named passageway
being smaller in cross-sectional area than the
first-named passageway whereby the ascend-
ing gases are momentarily retarded beneath
said opening.

10 In testimony whereof I hereunto affix my
signature.

DAVID LARKIN.
